(57) **CLAIM**

The ornamental design for an airstyler as shown and described.

DESCRIPTION

FIG. 1 is a front perspective view of an airstyler showing my new design in its environment of use;
FIG. 2 is a front view thereof with the outer casing removed;
FIG. 3 is a back view thereof with the outer casing removed;
FIG. 4 is an exploded left side view thereof with the right side view being a mirror image;

FIG. 5 is a left side view thereof with the outer casing removed, the right side view being a mirror image;
FIG. 6 is a top view thereof with the outer casing removed; and,

FIG. 7 is a bottom view thereof with the outer casing removed.
The broken lines illustrate portions of the airstyler that form no part of the claimed design.

The tonal differences in shading illustrate color contrast.
